(57) **CLAIM**

I claim the ornamental design for a raised bed garden system, as shown and described.

DESCRIPTION

This invention relates to devices for holding soil or other growing medium, in which plants may be grown.

FIG. 1 is a perspective view of a first embodiment of the raised bed garden system showing my new design;

FIG. 2 is a perspective view of the rail of the raised bed garden system showing the female end;

FIG. 3 is a perspective view of the rail from the male end;

FIG. 4 is a side view of the pin element of the raised bed garden system;

FIG. 5 is a perspective view of a second embodiment of the design shown in FIG. 1;

FIG. 6 is another perspective view showing the corner joint;

FIG. 7 is an enlarged, fragmentary view of the joint as shown in the view of FIG. 5;

FIG. 8 is a perspective view of a third embodiment of the design shown in FIG. 1; and,

FIG. 9 is another perspective view showing the corner joint. The elements are shown separately for ease and clarity of illustration.
